UNITED STATES PATENT OFFICE.

FRANK SCHUH, OF ALBANY, NEW YORK, ASSIGNOR OF ONE-HALF TO JOHN R. WILLIAMS, OF NEW YORK, N. Y.

FLOAT-VALVE.

1,064,386.

Specification of Letters Patent. Patented June 10, 1913.

Application filed April 6, 1912. Serial No. 688,939.

To all whom it may concern:

Be it known that I, FRANK SCHUH, a citizen of the United States, and a resident of Albany, in the county of Albany and State of New York, have invented a new and Improved Float-Valve, of which the following is a full, clear, and exact description.

The invention relates to flushing tanks for supplying water to water closets, urinals and other similar fixtures, and its object is to provide a new and improved float-controlled inlet valve, arranged to insure a proper opening and closing of the valve against the pressure of the water supply to direct the incoming water in a downward direction, to prevent upward squirting of the water, at the same time rendering the valve practically noiseless, to render the valve self-cleaning of sediment and other extraneous matter, and to prevent the valve from sticking.

For the purpose mentioned use is made of a valve, levers extending in opposite directions and controlling the valve, and a float connected with the ends of the levers.

A practical embodiment of the invention is represented in the accompanying drawings forming a part of this specification, in which similar characters of reference indicate corresponding parts in all the views.

Figure 1 is a perspective view of a float-valve as applied to a flushing tank, part of the latter being broken out; Fig. 2 is an enlarged sectional side elevation of the valve as applied to the bottom of the tank; Fig. 3 is a cross section of the valve seat; Fig. 4 is a side elevation of the valve; Fig. 5 is an enlarged side elevation of one end of the float and its connection with the corresponding valve lever; and Fig. 6 is an end view of the same.

The bottom A' of the flushing tank A is provided with an opening A² into which fits a nipple B' depending integrally from the under side of a cup-shaped body B seated on the upper surface of the bottom A'. Into the nipple B' screws the upper threaded end C' of a supply pipe C connected with a source of water supply, and on the threaded end C' screws a nut D against a washer E seated on the under surface of the bottom A' so as to fasten the body B in position on the bottom A' and

to properly connect the supply pipe C with the body B.

In the body B rises centrally a valve seat B² adapted to be engaged at its upper end by a washer F held on the under side of the top of a bell-shaped valve G extending within the cup-shaped body B, as plainly indicated in Fig. 2. The valve G is preferably provided in its side wall with openings G' for the passage of the water, it being understood that when the valve G is raised it opens the valve seat B² and allows water to pass through the seat B² against the under side of the bell-shaped valve G which directs the water in a downward direction against the bottom of the body B to then rise in the latter and pass into the tank A to fill the same to the usual normal level.

It will be noticed that when the valve G is in an open position and the water is directed in a downward direction by the valve G it prevents the water from squirting upward in the tank and practically renders the ball cock noiseless and at the same time any sediment that may settle in the bottom of the body B is washed out of the same by the force of the incoming water.

The top of the bell-shaped valve G is provided with an integral apertured boss G² into which extend the inner ends H² and H³ of float-controlled levers H and H' pivoted at I and I' on lugs B³ rising integrally from the upper edge of the cup-shaped body B. The levers H and H' are provided with upwardly-extending arms H⁴, H⁵ terminating in threaded ends H⁶, H⁷ on which screw nuts J, J' engaging brackets K and K' attached to the ends of a float L, made in cylindrical or other shape, and extending loosely between the arms H⁴ and H⁵ of the operating levers for the valve G. Each of the brackets K and K' is formed of two spaced members between which the corresponding threaded end H⁶ or H⁷ extends, and each member has a horizontal top K² and an upwardly and outwardly inclined bottom K³, and the nut J or J' is between the said top K² and the bottom K³.

When the water is discharged from the tank A then the float L falls with the water and in doing so the tops K² of the brackets K and K' bear on the upper surfaces of the nuts J, J' to impart a swinging motion to

the levers H and H' so that the valve G is lifted in a vertical direction to open the valve seat B^2 and thus allow water to pass into the tank A to fill the same to the normal level. As the water rises in the tank A to the normal level the float L rises with it and consequently the inclined bottoms K^3 of the brackets K and K' bear on the under sides of the nuts J and J' thus imparting a swinging motion to the levers H and H' in a reverse direction so that the levers move the valve G in a downward direction until the valve is finally seated on the valve seat B^2 and closes the same.

15 In order to insure a proper contact of the nuts J , J' with the tops K^2 and the bottoms K^3 of the brackets K , K' the upper and lower surfaces of the said nuts are preferably rounded off or made spherical, as

20 plainly indicated in Figs. 5 and 6.

The bell-shaped valve G is loosely fitted in the body B to permit ready escape of the water into the tank, and in order to prevent sidewise motion of the valve G at 25 the upper end thereof use is made of a screw G^2 screwing in the top of the boss G^2 to extend in close proximity to the inner segmental end faces of the ends H^2 , H^3 (see Fig. 2).

30 From the foregoing it will be seen that by the arrangement described the float L and the valve G move vertically up and down and consequently the valve is not liable to stick, and a proper opening and closing of the valve is insured.

35 The tank A is provided with the usual outlet valve N under the control of the operator and connected with a flushing pipe O leading to a water closet, urinal or other fixture to be flushed. A refilling pipe P connects with one side of the valve body B to allow refilling in case any of the fixtures of the tank are out of order, the pipe also serving as an overflow pipe to carry off 40 surplus water.

Having thus described my invention, I claim as new and desire to secure by Letters Patent:

1. A float valve for flushing tanks and 50 the like, comprising a cup-shaped body having a valve seat rising centrally in the body for the passage of the water into the tank, a bell-shaped valve extending into the said body and surrounding the said valve seat, the under side of the said valve being adapted to be seated on the upper end of the said valve seat, levers extending in opposite directions and fulcrumed on the said body, the said levers being connected with the top 55 of the said valve and the levers having upwardly-extending arms terminating in threaded ends provided with nuts, and a float provided at its ends with brackets engaging the said nuts.

35 2. A float valve for flushing tanks and the

like, comprising a cup-shaped body having a valve seat rising centrally in the body for the passage of the water into the tank, a bell-shaped valve extending into the said body and surrounding the said valve seat, the under side of the said valve being provided with a washer adapted to be seated on the upper end of the said valve seat, the top of the said valve being provided with an apertured boss, levers extending in opposite directions and fulcrumed on the said body, the inner ends of the said levers engaging the said apertured boss and the outer ends of the levers having upwardly-extending arms, and a float between the said arms and provided at its ends with brackets engaging the said arms to impart a simultaneous swinging motion to the said levers on the float rising and falling with the water in the tank.

3. A float valve for flushing tanks and the like, comprising a cup-shaped body having a valve seat rising centrally in the body for the passage of the water into the tank, a bell-shaped valve extending into the said body and surrounding the said valve seat, the under side of the said valve being provided with a washer adapted to be seated on the upper end of the said valve seat, the top of the said valve being provided with an apertured boss, levers extending in opposite directions and fulcrumed on the said body, the inner ends of the said levers engaging the said apertured boss and the outer ends of the levers having upwardly-extending arms terminating in threaded ends provided with nuts, and a float between the said arms and provided at its ends with brackets engaging the said nuts.

4. A float valve for flushing tanks and the like, comprising a valve controlling the inflow of the water into the tank, levers extending in opposite directions and connected at one end with the said valve, the levers having upwardly-extending arms terminating in threaded ends, nuts screwing on the said threaded ends, a float, and brackets on the ends of the float, each bracket having a horizontal top member and an outwardly and upwardly inclined bottom member, the said top and bottom members of the brackets being adapted to be engaged by the said nuts.

5. A float valve for flushing tanks and the like, comprising a valve controlling the inflow of the water into the tank, levers extending in opposite directions and connected at one end with the said valve, the levers having upwardly-extending arms terminating in threaded ends, nuts screwing on the said threaded ends, a float, and brackets on the ends of the float, each bracket having a horizontal top member and an outwardly and upwardly inclined bottom member, the said top and bottom

members of the brackets being adapted to be engaged by the said nuts, the top and bottom faces of the said nuts being rounded off.

6. A float valve for flushing tanks, comprising a cup-shaped body having a valve seat rising centrally in the body for the passage of the water into the tank, a bell-shaped valve extending into the said body and surrounding the valve seat, the under 10 side of the said valve being adapted to be seated on the upper end of the said valve seat, levers extending in opposite directions and fulcrumed on the said body, the said levers being connected with the top of the

said valve and the levers having upwardly-extending arms, and a float provided on its ends with brackets having inclined members engaging the upper ends of the said arms for imparting a swinging motion to the levers on the rise of the float in the said 20 tank.

In testimony whereof I have signed my name to this specification in the presence of two subscribing witnesses.

FRANK SCHUH.
